(57) **CLAIM**

(51) LOC (7) Cl. **07-05**

The ornamental design for an electric iron, as shown and described.

(52) U.S. Cl. **D32/70**

DESCRIPTION

(58) Field of Search D32/68-72; 38/74-75,

FIG. 1 is a top perspective view of an electric iron of the present invention;

38/77.1-77.8, 77.81, 77.9, 88, 90; 219/245-248

FIG. 2 is a front view thereof;

(56) **References Cited**

FIG. 3 is a top view thereof;
